Specification for Design.

Patented Dec. 6, 1921.

Application filed August 26, 1921. Serial No. 495,816. Term of patent 7 years.

To all whom it may concern:

Be it known that I, SAMUEL H. PAGE, a subject of the King of Great Britain, residing at Stratford, county of Fairfield, State of Connecticut, have invented a new, original, and ornamental Design for Lace, of which the following is a specification, reference being had to the accompanying drawing, forming a part thereof.

The figure is a plan view of a piece of lace constituting my new design.

I claim:

The ornamental design for lace substantially as shown.

In testimony whereof I affix my signature.

SAMUEL H. PAGE.
